(57) CLAIM

The ornamental design for the delineator post cover, as shown and described.

DESCRIPTION

FIG. 1 is a front-perspective view of a delineator post cover embodying my new design;

FIG. 2 is a back-perspective view of the delineator post cover of FIG. 1;

FIG. 3 is a front-side view of the delineator post cover of FIG. 1;

FIG. 4 is a back-side view of the delineator post cover of FIG. 1;

FIG. 5 is a right-side view of the delineator post cover of FIG. 1;

FIG. 6 is a left-side view of the delineator post cover of FIG. 1;

FIG. 7 is a top-side view of the delineator post cover of FIG. 1; and,

FIG. 8 is a bottom-side view of the delineator post cover of FIG. 1.

The broken lines show portions of the article not claimed and form no part of the claimed design.
